UNITED STATES PATENT OFFICE

168,970

AWNING

Sam Rosenmutter, Los Angeles, Calif.

Application March 20, 1952, Serial No. 18,975

Term of patent 14 years

(Cl. D21—6)

To all whom it may concern:

Be it known that I, Sam Rosenmutter, a citizen of the United States of America, residing at Los Angeles, in the county of Los Angeles, State of California, have invented a new, original, and ornamental Design for an Awning, of which the following is a specification, reference being had to the accompanying drawings, forming a part thereof.

I claim:

The ornamental design for an awning, substantially as shown.

SAM ROSENMUTTER.
